ATTORNEYS

UNITED STATES PATENT OFFICE.

DIWITZ ETIENNE, OF NEW YORK, N. Y.

DESIGN FOR A BOTTLE.

SPECIFICATION forming part of Design No. 20,962, dated July 28, 1891.

Application filed June 9, 1891. Serial No. 395,723. Term of patent 3½ years.

To all whom it may concern:

Be it known that I, DIWITZ ETIENNE, a citizen of the United States, residing at New York city, in the county and State of New York, have invented and produced a new and original Design for a Bottle, of which the following is a specification, reference being had to the accompanying drawing, forming part thereof, which represents a perspective view 10 of a bottle embodying my design.

The principal feature of the design consists of a pedestal-like figure A and a bust figure B, apparently resting upon the pedestal figure, which bust figure simulates in outline a typical representation of the head and shoulders 15

of Columbus, the reputed discoverer of America.

The adjunctive or minor feature of the design consists of a base figure C, apparently constituting a crown or cap for the pedestal 20 figure and a support for the bust figure. The pedestal figure has the appearance of a chambered body.

I claim—

A design for a bottle, substantially as herein shown and described.

DIWITZ ETIENNE.
